GAS-OPERATED SELF-LOADING FIREARM

Harry L. Crockett, New Haven, Conn., assignor to
Olin Industries, Inc., New Haven, Conn., a corporation of Delaware

Application February 1, 1945, Serial No. 575,602

9 Claims.

(Cl. 42—3)

The present invention relates to improvements in self-loading firearms and relates more particularly to improvements in self-loading firearms of the type wherein gas-pressure from the bore of the barrel serves to actuate a piston which, in turn, actuates the breech-bolt and associated features of the firearm to effect the extraction and ejection of the just-fired cartridge, preparatory to the automatic reloading of the firearm with a fresh cartridge.

One of the objects of the present invention is to provide a superior firearm of the character referred to and in which the parts are constructed and arranged to minimize distortion of the bolt-operating slide under the stresses imposed thereon by the gas-operated piston.

Another object of the present invention is to provide a gas-operated self-loading firearm with a superior construction and arrangement of parts whereby the gas-operated piston applies its thrust upon a bolt-operating slide at a point laterally intermediate the guide-means for the said slide and the portion of the said slide which is operatively connected to the breech-bolt to operate the same, to thereby minimize flexing strains upon the said action-slide and to insure reliable operation of the firearm.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a broken elevational view of the central portion of a gas-operated self-loading firearm embodying the present invention and looking toward the right side thereof;

Fig. 2 is a top or plan view of the showing of Fig. 1;

Fig. 3 is a view similar to Fig. 1 but looking toward the firearm-structure from the left side thereof;

Fig. 4 is a view of the showing of Fig. 3 mainly in underside and partly in horizontal section on the line 4—4 of Fig. 3;

Fig. 5 is a transverse sectional view taken on the line 5—5 of Fig. 3;

Fig. 6 is a similar view taken on the line 6—6 of Fig. 3; and

Fig. 7 is a broken perspective view of the forward-portion of the action-slide.

The particular gas-operated self-loading firearm herein chosen for purposes of illustrating

one form of the present invention, includes a receiver 10, a barrel 11, a trigger-plate unit 12, an action-slide 13, and a breech-bolt 14.

The receiver 10 above referred to includes a top-wall 15 and integral side-walls 16 and 17. The forward-portions of the top-wall 15 and the side-wall 17 are cut away to provide an ejection-opening 18. The said ejection-opening is closed by the breech-bolt 14 when the latter is in its forward or breech-closing position, but the said ejection-opening is open when the said breech-bolt is in its rearward position, in a manner common in the art.

The side-wall 16 of the receiver 10 is formed adjacent the forward end of the ejection-opening 18, with a forwardly-facing locking-abutment 19, while the opposite side-wall 17 is formed at a similar location with a forwardly-facing locking-abutment 20. The locking-abutments 19 and 20 are adapted to be engaged by the respective rear-faces or edges of bolt-locking lugs 21 and 22. The said bolt-locking lugs 21 and 22 are formed integral with and respectively project in substantially-diametrically-opposite directions from the forward-portion of the breech-bolt 14.

Extending radially outwardly from the outer-end of the bolt-locking lug 22 is an integral bolt-operating lug 23 which projects into a cam-recess 24 formed in the inner-face of the enlarged rear-portion 25 of the action-slide 13 before referred to.

The bolt-operating lug 23 of the breech-bolt 14 and the cam-recess 24 in the rear-portion 25 of the action-slide 13, generally correspond to features embodied in the well-known Garand military rifle, and coact in such manner that when the action-slide 13 is moved rearwardly from the position in which it is shown in the drawings, the said cam-recess will coact with the bolt-operating lug 23 to first turn the breech-bolt 14 in a clockwise direction (as viewed from the front) to disengage the bolt-locking lugs 21 and 22 respectively from the locking-abutments 19 and 20 of the receiver 10. Following this unlocking movement of the breech-bolt, the coaction of the bolt-operating lug 23 and the surfaces of the cam-recess 24 will then effect the direct rearward movement of the breech-bolt 14 until the latter reaches the limit of its rearward movement. Conversely, when the action-slide is moved forwardly, following the above-described rearward movement thereof, the coaction of the bolt-operating lug 23 and the cam-recess 24 will first draw the said breech-bolt forwardly until such time as the respective rear-faces of its bolt-locking lugs 21 and 22 respectively register with the locking-

abutments 19 and 20 of the receiver 10, whereupon the breech-bolt 14 will be turned transversely in a counterclockwise direction to again lock the breech-bolt in its breech-closing position.

The enlarged rear-portion 25 of the action-slide 13 is integrally connected by means of a bar-portion 26 to a crosshead 27 forming the foremost part of the action-slide 13. The rear-portion 25 and the bar-portion 26 of the action-slide 13 are mounted for reciprocation adjacent the right side of the barrel 11, and the crosshead 27 extends laterally from the forward-portion of the said bar-portion 26 beneath the said barrel to a point adjacent the left side of the latter. The upper-face of the crosshead 27 is formed with a longitudinal upwardly-opening clearance-groove 28 which serves to accommodate the adjacent portion of the barrel 11 and permit the free reciprocating movement of the said crosshead with respect to the said barrel.

At a point forwardly of the receiver 10 and also forwardly of the crosshead 27 of the action-slide 13, the barrel 11 is formed with an integral depending cylinder-lug 29 which has sufficient breadth to extend laterally beyond either side of the barrel 11 proper, as is especially well shown in Fig. 6. The said cylinder-lug is formed at a point directly beneath the center line of the barrel 11 with a downwardly-opening internally-threaded coupling socket 30 which is adapted to receive any suitable coupling-screw (not shown) which may serve to attach a suitable stock (also not shown) to the barrel 11.

In its lower right-hand portion, the cylinder-lug 29 is formed with a piston-chamber 31 which has its axis extending in substantial parallelism with the longitudinal axis of the barrel 11 and which opens through the rear-face of the cylinder-lug 29, as is especially well shown in Fig. 4. Reciprocating in the piston-chamber 31 is a piston generally designated by the reference character 32 and including a relatively-large-diametered head 33 and an integral relatively-small-diametered stem 34. The head 33 constitutes the forward-portion of the piston 32, while the stem 34 projects rearwardly and has its rear-end normally engaged with the forward-face of the crosshead 27 of the action-slide 13.

The rear-portion of the piston-chamber 31 in the cylinder-lug 29 is enlarged and internally threaded to receive a ring-like externally-threaded stop-member 35 adapted to have its forward-face engaged by the rear-face of the head 33 of the piston 32 when the said piston is driven rearwardly, in a manner as will herein-after appear.

For the purpose of causing gas under pressure to impinge against the forward end of the piston 32, to thus drive the said piston rearwardly, the cylinder-lug 29 of the barrel 11 is formed with an inclined gas-passage 36 which communicates at its lower end with the forward end of the piston-chamber and which communicates at its upper end with the bore 37 of the barrel 11, as is indicated in Figs. 1, 4 and 6.

In its lower left-hand portion, the cylinder-lug 29 of the barrel 11 is formed with a socket 38 extending through the said cylinder-lug from front to rear in substantial parallelism with the bore 37 of the barrel 11. Supported in the socket 38 in the cylinder-lug 29 is the forward end of a guide-rod 39 which has its rear end threaded and entered into an internally-threaded socket 40 formed in the forward lower-portion of the receiver 10 adjacent the left side thereof, as is

especially well shown in Fig. 4. As thus constructed and arranged, the said guide-rod spans the gap between the forward end of the receiver 10 and the rear-face of the cylinder-lug 29, and has its forward and rear ends respectively firmly supported in the said cylinder-lug 29 and the receiver 10.

The guide-rod 39 above referred to extends with a free sliding fit through a bearing-passage 41 formed in the lower-left-portion of the crosshead 27 of the action-slide 13, as is especially well shown in Figs. 4 and 5.

In its lower right-hand portion, the crosshead 27 of the action-slide 13 is formed with a rearwardly-opening socket 42 which is adapted to receive a stud 43 formed integral with and projecting forwardly from the front end of a breech-closing plunger 44. At the base of the said stud 43, the breech-closing plunger 44 just referred to is formed with an integral collar 45 having its forward-face engaged with the rear-face of the crosshead 27 and having its rear-face, in turn, engaged by the forward end of a helical breech-closing spring 46. The said breech-closing spring 46 encircles the main-portion of the said plunger 44 and extends at its rear into a forwardly-opening spring-pocket 47 formed in the lower right-hand portion of the right side-wall 11 of the receiver 10, as is especially well shown in Fig. 4.

The rear end of the breech-closing plunger 44 is also normally entered into the forward-portion of the spring-pocket 47 and is adapted to slide further rearwardly into the said spring-pocket when the action-slide 13 is moved rearwardly.

As thus constructed and arranged, the breech-closing spring 46, acting through the intermediary of the breech-closing plunger 44 and the crosshead 27, acts to yieldingly hold the action-slide 13 in its forward position and hence, also, to yieldingly hold the breech-bolt 14 in its breech-closing position.

When the firearm is discharged in any suitable manner, gas under pressure will pass from the bore 37 of the barrel 11 into the forward end of the piston-chamber 31 in the cylinder-lug 29. The said gas will impinge against the forward-face of the head 33 of the piston 32 and drive the said piston rearwardly a short distance until the rear-face of the head 33 engages with the forward-face of the stop-member 35. The described rearward movement of the piston 32 will cause the rear-face of the stem 34 to drive against the forward-face of the crosshead 27 at a point closely in line with the breech-closing spring 46 but at a point laterally intermediate the said spring and the guide-rod 39.

The described rearward movement of the piston 32 will drive the action-slide rearwardly and impart thereto a rearward movement far in excess of the relatively-short movement of the piston 32 itself. As the action-slide moves rearwardly, the crosshead 27 will slide on the guide-rod 39 and will also drive the breech-closing plunger 44 rearwardly, to effect the compression of the breech-closing spring 46.

The rearward movement of the action-slide 13 will unlock and retire the breech-bolt 14. Upon the completion of its rearward movement, the action-slide 13 will be reversed and moved forwardly by the action of the breech-closing spring 46, to thereby again restore the parts to the positions in which they are shown in the drawings, preparatory to another discharge of the firearm.

By locating the guide-rod 39, piston 32 and breech-closing spring 46 in the manner shown

and described, the said piston is caused to exert its relatively-violent rearward force in substantial alignment with both the breech-closing springs 46 and the bar-portion 26 of the action-slide, while the opposite side of the crosshead 27 is being steadied and guided by the guide-rod 39. In this manner, the distortion of the action-slide is so minimized as to enable the action-slide to function smoothly and without requiring that the said action-slide be excessively heavy in order to withstand excessive flexural and cramping strains.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A gas-operated self-loading firearm, including in combination: a receiver; a barrel projecting forwardly from the said receiver; a cylinder-lug depending from the said barrel at a point forwardly of the said receiver and formed with a rearwardly-opening piston-chamber having its longitudinal axis extending in substantial parallelism with the longitudinal axis of the said barrel, the longitudinal axis of the said piston-chamber being located in a plane to one side of the vertical longitudinal plane extending through the longitudinal axis of the said barrel; a guide-rod having its longitudinal axis extending in substantial parallelism with the longitudinal axis of the said barrel and located on the opposite side of the vertical longitudinal plane extending through the longitudinal axis of the said barrel, the said guide-rod having its forward-end engaged with the said cylinder-lug and having its rear-end engaged with the forward-portion of the said receiver; a breech-bolt movable longitudinally in the said receiver; an action-slide mounted for longitudinal reciprocation along one side of the said receiver and having a bearing-portion slidably engaging with the said guide-rod, the said action-slide being operatively connected to the said breech-bolt for moving the same; a piston movable in the piston-chamber of the said cylinder-lug and normally engaged with a forward-portion of the said action-slide to drive the latter rearwardly; and gas-conducting means extending between the bore of the said barrel and the forward-portion of the piston-chamber in the said barrel-lug.

2. A gas-operated self-loading firearm, including in combination: a receiver; a barrel projecting forwardly from the said receiver; a cylinder-lug depending from the said barrel at a point forwardly of the said receiver and formed with a rearwardly-opening piston-chamber having its longitudinal axis extending in substantial parallelism with the longitudinal axis of the said barrel, the longitudinal axis of the said piston-chamber being located in a plane to one side of the vertical longitudinal plane extending through the longitudinal axis of the said barrel; a guide-rod having its longitudinal axis extending in substantial parallelism with the longitudinal axis of the said barrel and located on the opposite side of the vertical longitudinal plane extending through the longitudinal axis of the said barrel, the said guide-rod having its forward-end engaged with

the said cylinder-lug and having its rear-end engaged with the forward-portion of the said receiver; a breech-bolt movable longitudinally in the said receiver; an action-slide mounted for longitudinal reciprocation along the side of the firearm-structure on which the said piston-chamber is located, the said action-slide being operatively connected at its rear with the said breech-bolt and having adjacent its forward-end a bearing-portion slidably engaging with the said guide-rod; a piston movable in the piston-chamber of the said cylinder-lug and normally engaged with a forward-portion of the said action-slide to drive the latter rearwardly; and gas-conducting means extending between the bore of the said barrel and the forward-portion of the piston-chamber in the said barrel-lug.

3. A gas-operated self-loading firearm, including in combination: a receiver; a barrel projecting forwardly from the said receiver; a cylinder-lug depending from the said barrel at a point forwardly of the said receiver and formed with a rearwardly-opening piston-chamber having its longitudinal axis extending in substantial parallelism with the longitudinal axis of the said barrel, the longitudinal axis of the said piston-chamber being located in a plane to one side of the vertical longitudinal plane extending through the longitudinal axis of the said barrel; a guide-rod having its longitudinal axis extending in substantial parallelism with the longitudinal axis of the said barrel and located on the opposite side of the vertical longitudinal plane extending through the longitudinal axis of the said barrel, the said guide-rod having its forward-end engaged with the said cylinder-lug and having its rear-end engaged with the forward-portion of the said receiver; a breech-bolt movable longitudinally in the said receiver; an action-slide mounted for longitudinal reciprocation along one side of the said receiver and having a head-portion adjacent its forward-end which head-portion is provided with a bearing-portion slidably engaging with the said guide-rod, the said action-slide being operatively connected adjacent its rear-end to the said breech-bolt for moving the same; a piston movable in the piston-chamber of the said cylinder-lug and normally engaged with the head-portion of the said action-slide to drive the action-slide rearwardly; and gas-conducting means extending between the bore of the said barrel and the forward-portion of the piston-chamber in the said barrel-lug.

4. A gas-operated self-loading firearm, including in combination: a receiver; a barrel projecting forwardly from the said receiver; a cylinder-lug depending from the said barrel at a point forwardly of the said receiver and formed with a rearwardly-opening piston-chamber having its longitudinal axis extending in substantial parallelism with the longitudinal axis of the said barrel, the longitudinal axis of the said piston-chamber being located in a plane to one side of the vertical longitudinal plane extending through the longitudinal axis of the said barrel; a guide-rod having its longitudinal axis extending in substantial parallelism with the longitudinal axis of the said barrel and located on the opposite side of the vertical longitudinal plane extending through the longitudinal axis of the said barrel, the said guide-rod having its forward-end engaged with the said cylinder-lug and having its rear-end engaged with the forward-portion of the said receiver; a breech-bolt movable longi-

tudinally in the said receiver; an action-slide mounted for longitudinal reciprocation along the side of the firearm-structure on which the said piston-chamber is located and having a head-portion adjacent its forward-end which head-portion extends transversely beneath the barrel into bearing engagement with the said guide-rod, the said action-slide being operatively connected adjacent its rear-end to the said breech-bolt for moving the same; a piston movable in the piston-chamber of the said cylinder-lug and normally engaged with the head-portion of the said action-slide to drive the action-slide rearwardly; and gas-conducting means extending between the bore of the said barrel and the forward-portion of the piston-chamber in the said barrel-lug.

5. A gas-operated self-loading firearm, including in combination: a receiver; a barrel projecting forwardly from the said receiver; a cylinder-lug depending from the said barrel at a point forwardly of the said receiver and formed with a rearwardly-opening piston-chamber having its longitudinal axis extending in substantial parallelism with the longitudinal axis of the said barrel, the longitudinal axis of the said piston-chamber being located in a plane to one side of the vertical longitudinal plane extending through the longitudinal axis of the said barrel; a guide-rod having its longitudinal axis extending in substantial parallelism with the longitudinal axis of the said barrel and located on the opposite side of the vertical longitudinal plane extending through the longitudinal axis of the said barrel, the said guide-rod having its forward-end engaged with the said cylinder-lug and having its rear-end engaged with the forward-portion of the said receiver; a breech-bolt movable longitudinally in the said receiver; an action-slide mounted for longitudinal reciprocation along one side of the said receiver and having a bearing-portion slidably engaging with the said guide-rod, the said action-slide being operatively connected to the said breech-bolt for moving the same; a helical breech-closing spring thrusting forwardly upon the said action-slide and extending in substantial parallelism with the said guide-rod but located on the opposite side of the firearm-structure therefrom; a piston movable in the piston-chamber of the said cylinder-lug and normally engaged with a forward-portion of the said action-slide to drive the latter rearwardly; and gas-conducting means extending between the bore of the said barrel and the forward-portion of the piston-chamber in the said barrel-lug.

6. A gas-operated self-loading firearm, including in combination: a receiver; a barrel projecting forwardly from the said receiver; a cylinder-lug depending from the said barrel at a point forwardly of the said receiver and formed with a rearwardly-opening piston-chamber having its longitudinal axis extending in substantial parallelism with the longitudinal axis of the said barrel, the longitudinal axis of the said piston-chamber being located in a plane to one side of the vertical longitudinal plane extending through the longitudinal axis of the said barrel; a guide-rod having its longitudinal axis extending in substantial parallelism with the longitudinal axis of the said barrel and located on the opposite side of the vertical longitudinal plane extending through the longitudinal axis of the said barrel, the said guide-rod having its forward-end engaged with the said cylinder-lug and having its rear-end engaged with the forward-portion of the said re-

ceiver; a breech-bolt movable longitudinally in the said receiver; an action-slide mounted for longitudinal reciprocation along the side of the firearm-structure on which the said piston-chamber is located, the said action-slide being operatively connected at its rear with the said breech-bolt and having adjacent its forward-end a bearing-portion slidably engaging with the said guide-rod; a helical breech-closing spring thrusting forwardly upon the said action-slide and extending in substantial parallelism with the said guide-rod but located on the opposite side of the firearm-structure therefrom; a piston movable in the piston-chamber of the said cylinder-lug and normally engaged with a forward-portion of the said action-slide to drive the latter rearwardly; and gas-conducting means extending between the bore of the said barrel and the forward-portion of the piston-chamber in the said barrel-lug.

7. A gas-operated self-loading firearm, including in combination: a receiver; a barrel projecting forwardly from the said receiver; a cylinder-lug depending from the said barrel at a point forwardly of the said receiver and formed with a rearwardly-opening piston-chamber having its longitudinal axis extending in substantial parallelism with the longitudinal axis of the said barrel, the longitudinal axis of the said piston-chamber being located in a plane to one side of the vertical longitudinal plane extending through the longitudinal axis of the said barrel; a guide-rod having its longitudinal axis extending in substantial parallelism with the longitudinal axis of the said barrel and located on the opposite side of the vertical longitudinal plane extending through the longitudinal axis of the said barrel, the said guide-rod having its forward-end engaged with the said cylinder-lug and having its rear-end engaged with the forward-portion of the said receiver; a breech-bolt movable longitudinally in the said receiver; an action-slide mounted for longitudinal reciprocation along one side of the said receiver and having a head-portion adjacent its forward-end which head-portion is provided with a bearing-portion slidably engaging with the said guide-rod, the said action-slide being operatively connected adjacent its rear-end to the said breech-bolt for moving the same; a helical breech-closing spring thrusting forwardly upon the head-portion of the said action-slide and extending in substantial parallelism with the said guide-rod but located on the opposite side of the firearm-structure therefrom; a piston movable in the piston-chamber of the said cylinder-lug and normally engaged with the head-portion of the said action-slide to drive the action-slide rearwardly; and gas-conducting means extending between the bore of the said barrel and the forward-portion of the piston-chamber in the said barrel-lug.

8. A gas-operated self-loading firearm, including in combination: a receiver; a barrel projecting forwardly from the said receiver; a cylinder-lug depending from the said barrel at a point forwardly of the said receiver and formed with a rearwardly-opening piston-chamber having its longitudinal axis extending in substantial parallelism with the longitudinal axis of the said barrel, the longitudinal axis of the said piston-chamber being located in a plane to one side of the vertical longitudinal plane extending through the longitudinal axis of the said barrel; a guide-rod having its longitudinal axis extending in substantial parallelism with the longitudinal axis of the said barrel-lug.

said barrel and located on the opposite side of the vertical longitudinal plane extending through the longitudinal axis of the said barrel, the said guide-rod having its forward-end engaged with the said cylinder-lug and having its rear-end engaged with the forward-portion of the said receiver; a breech-bolt movable longitudinally in the said receiver; an action-slide mounted for longitudinal reciprocation along the side of the firearm-structure on which the said piston-chamber is located and having a head-portion adjacent its forward-end which head-portion extends transversely beneath the barrel into bearing engagement with the said guide-rod, the said action-slide being operatively connected adjacent its rear-end to the said breech-bolt for moving the same; a helical breech-closing spring thrusting forwardly upon the head-portion of the said action-slide and extending in substantial parallelism with the said guide-rod but located on the opposite side of the firearm-structure therefrom; a piston movable in the piston-chamber of the said cylinder-lug and normally engaged with the head-portion of the said action-slide to drive the action-slide rearwardly; and gas-conducting means extending between the bore of the said barrel and the forward-portion of the piston-chamber in the said barrel-lug.

9. A gas-operated self-loading firearm, including in combination: a receiver; a barrel projecting forwardly from the said receiver; a cylinder-

lug depending from the said barrel at a point forwardly of the said receiver and formed with a rearwardly-opening piston-chamber and with a rod-receiving passage, both the said piston-chamber and the rod-receiving passage extending in substantial parallelism with the longitudinal axis of the said barrel and respectively located on opposite sides of the vertical longitudinal plane extending through the longitudinal axis of the said barrel; a guide-rod having its longitudinal axis extending in substantial parallelism with the longitudinal axis of the said barrel and having its rear-end threadedly engaged with the forward-portion of the said receiver and having its forward-end located in the rod-receiving passage of the said cylinder-lug; an action-slide mounted for longitudinal reciprocation along one side of the said receiver and having a head-portion adjacent its forward-end which head-portion is provided with a bearing-portion slidably engaging with the said guide-rod, the said action-slide being operatively connected adjacent its rear-end to the said breech-bolt for moving the same; a piston movable in the piston-chamber of the said cylinder-lug and normally engaged with the head-portion of the said action-slide to drive the action-slide rearwardly; and gas-conducting means extending between the bore of the said barrel and the forward-portion of the piston-chamber in the said barrel-lug.

HARRY L. CROCKETT.
